(57) CLAIM

The ornamental design for a handle of table tennis racket, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a handle of a table tennis racket; and,

FIG. 2 is a front perspective view.

The broken line portions in FIGS. 1-2 are included to show unclaimed subject matter only and form no part of the claimed design.
